His Attorney.

UNITED STATES PATENT OFFICE.

WILLIAM D. COOLIDGE, OF SCHENECTADY, NEW YORK, ASSIGNOR TO GENERAL ELECTRIC COMPANY, A CORPORATION OF NEW YORK.

X-RAY APPARATUS.

Application filed July 9, 1920. Serial No. 395,088.

To all whom it may concern:

Be it known that I, WILLIAM D. COOLIDGE, a citizen of the United States, residing at Schenectady, in the county of Schenectady, State of New York, have invented certain new and useful Improvements in X-Ray Apparatus, of which the following is a specification.

The present invention comprises an X-ray apparatus which is particularly suited for radiography altho it is not limited in its use to this particular purpose.

When utilizing X-rays for diagnostic purposes, it is particularly desirable to secure a constant radiographic effect for a given setting so that for comparison purposes the resulting radiographs may be of equal density. For example, for a constant impressed voltage and X-ray producing current, and for a given subject, an X-ray tube operating by electron conduction substantially independently of gaseous ionization, will always produce a radiograph of the same density for a given exposure. As explained by Prof. J. S. Shearer in the American Journal of Roentgenology, vol. 3 (1916), page 300, the radiographic effect may be expressed as follows in terms of current (I), time (T), voltage (V), and distance (D)

$$R.E. = \frac{IT \times V}{D^2}$$

The distance between the X-ray source and the photographic plate or film can readily be maintained constant. It would appear in view of this that with a given patient, a doctor or dentist could always get the same sort of radiograph by the use of a simple time switch. As a matter of fact, this ideal condition is obtainable only in a laboratory under carefully controlled conditions. Ordinarily the available current supply is extremely variable in voltage, and consequently a time switch alone is insufficient to give a substantially constant radiographic effect.

In accordance with my invention, I have provided an X-ray apparatus constructed to give a substantially constant radiographic effect even with a variable supply voltage. The novel structural features of my invention will be pointed out with particularity in the appended claims.

My invention will be described in detail in the following specification taken in connection with the accompanying drawings in which Fig. 1 illustrates diagrammatically a system embodying my invention utilizing an ordinary time switch; Fig. 2 is a diagram of a set of curves showing the currents in the transformer furnishing current for heating the cathode of the X-ray tube; Fig. 3 is a more highly developed system containing a special time switch with a constant or substantially constant electron emission at the cathode; and Fig. 4 illustrates diagrammatically one form of cathode heating transformer suitable for use in my improved apparatus.

The system shown in Fig. 1 contains an X-ray tube 1 of the hot cathode type supplied with heating currents from a special transforming apparatus 3 which is designed to give a heating effect which varies inversely with the supply voltage. In the construction illustrated in Fig. 1 and Fig. 4, the transformer 3 is provided with two primary windings 4 and 5.

As illustrated in Fig. 4, the primary windings 4 and 5 are located on separate cores 6 and 7. The core 6 is rectangular and is so constructed as to provide a highly saturated magnetic circuit for its primary winding 4 and secondary winding 8 with normal voltage on the apparatus. The arrangement of the core and windings illustrated, provides for an appreciable magnetic leakage between the windings. The section 5 of the primary winding is wound on an open magnetic core 7 with an auxiliary secondary winding 9. The core 7 is so constructed as to operate far below saturation. The change of voltage at the terminals of the auxiliary secondary winding 9 takes place at a fairly low rate as the primary voltage changes. The core 7 has been shown as an open magnetic core to illustrate this feature. The two primary transformer windings 4 and 5 are connected in series with each other and by conductors 10 and 11 to the source of energy represented by the mains 12 and 13. The main secondary winding 8 and the auxiliary secondary winding 9 are also connected in series, but are so connected that the induced electromotive forces oppose each other. The terminals 14, 15 of these windings are con-

5 connected in series with an adjustable resistance 16, (Fig. 1) to the primary of a transformer 17, the secondary of which is connected by conductors 18, 19, to the terminals of the cathode 2 of the X-ray tube. In some cases the transformer 17 may be omitted.

10 The sum of the magnetic fluxes in the saturated and unsaturated magnetic circuit varies in proportion to the voltage variation of the supply circuit 12, 13, but the fluxes in the two secondary windings vary at different rates. By properly proportioning the secondary windings, which are connected in opposition, the sum of the voltage in the 15 conductors 14, 15 may be made to decrease as the voltage impressed on the primary windings 4, 5 increases, in such measure as to produce a substantially constant radiographic effect.

20 The operation of the filament lighting transformer will be more clearly understood from the diagram of electromotive forces shown in Fig. 2. The voltages induced in the main and auxiliary secondary windings 25 are measured along the vertical line 22 and the currents in the primary windings are measured along the horizontal line 23. Since the core 6 is highly saturated at normal voltages the total electromotive force 30 induced in the main secondary winding 8 varies with the variations of primary current in the general manner represented by the curve 24, 25. A change of the electromotive force in the auxiliary secondary winding 9 is indicated by the curve 26. This curve 26 is drawn below the horizontal zero line to indicate that this electromotive force opposes the electromotive force of the curve 24, 25, the main and auxiliary secondaries 8, 9 being connected in opposition. The resultant secondary voltages across the terminals 14 and 15 therefore may be represented by the curve 27, 28. This resultant curve rises rapidly at first over the portion 45 27, and then bends downwardly. As the current in the primary winding increases with an increase of impressed electromotive force, the voltage in the conductors 14, 15 decreases.

50 The cathode 2 and anode 20 of the X-ray tube are connected by conductors 63, 64 to a high potential transformer 65, the primary of which is connected by conductors 66, 67, to the mains 12, 13. In series with the primary of the transformer 65 is a time switch 68, which has been diagrammatically shown in the drawings, and may be of any preferred construction. When the time switch is set to give an exposure of given length, 55 should the voltage in the main conductors 12, 13 vary, for example, should it increase, thereby increasing the voltage across the terminals of the X-ray tube, and consequently increasing the penetrability of the X-rays, 60 then by the action of the described construc-

tion in the filament lighting transformer, the temperature of the cathode decreases at such rate that the resulting radiographic effect for the given exposure is substantially constant over a working range. 70

Conversely, a decrease of voltage of the supply source will result in an increase of voltage of the filament lighting current, increasing the temperature of the cathode and thereby increasing the milliamperage of the 75 current through the tube, and thus compensating for the decrease of impressed voltage so as to give over a working range a substantially constant radiographic effect. Instead of varying the current through the 80 tube the other member of the current-time factor may be varied, while the current is maintained constant.

In accordance with a modification of my invention illustrated in Fig. 3, the X-ray 85 tube cathode is heated with current of substantially constant voltage giving a constant cathode temperature giving a substantially constant current-carrying capacity at operating voltages sufficiently high to yield saturation currents and the length of time of operation of the tube is varied inversely in proportion to the square of the voltage in order to give a substantially constant radiographic effect. The current for heating the 90 cathode may be obtained from a separate source of constant voltage, as for example, a battery, or if desired, the filament lighting apparatus described in connection with Fig. 1 may be modified by properly proportioning the secondary windings 8 and 9 to give a substantially constant voltage in the filament lighting circuit over a working range. The X-ray tube and connections have not 95 been illustrated in Fig. 3 as they would appear diagrammatically to be the same as in Fig. 1, but the secondaries 8 and 9 are so proportioned that the resultant of the electromotive forces of the coils 8 and 9 will produce current of substantially constant 100 voltage over the operating range. In other words, referring to Fig. 2, the part 28 of the resultant current 27 will be substantially horizontal. In place of the time switch 68, I employ a switch, as illustrated in considerable detail in Fig. 3, which gives a variable 105 time interval, as will now be more fully described.

Referring to Fig. 3, it will be observed 110 that the time switch has a motor element of the induction meter type comprising a rotating circular disc 30 supported on a vertical shaft 31 and acted upon by electromagnets 32, 32'. The core of the magnet 32 above the disc 30 is horseshoe shaped and 115 mounted upon its legs are electromagnetic coils 33, 34, which are connected in series with each other and by conductors 35, 36 across the supply conductors 12, 13. The core of the magnet 32' below the disc 30 is 120

E-shaped. Mounted upon its central leg is a coil 37 connected by the conductors 38, 39 across the supply mains 12, 13 in parallel with the series coils 33, 34, thereby obtaining a motor effect in the well known way. The permanent magnets 40, 41, exercise a magnetic braking or damping effect upon the motor disc 30, so that with a variation of voltage the speed of rotation will vary directly with the square of the voltage changes.

10 A movable plate 43 pivoted upon a support 42 carrying the contact making elements of the switch is adapted to be meshed with the gear 44 carried by the shaft 31, by 15 means of a clutch mechanism consisting of an electromagnet 45 and an armature 46. The magnet 45 is connected by conductors 47, 48 and 47', to a source of current represented by conductors 13, 12. These conductors 48, 49 may be connected in series with the primary of the transformer 23 as indicated in Fig. 3.

When the hand switch 50 is closed the electromagnet 45 is energized causing gear 25 train 51 to mesh with the spur gear 44 and producing a clockwise revolution of the gear wheel 52. Mounted upon this gear wheel 52 is a pin 53 which engages with a contact 54 when the gear wheel 52 is rotated in a clockwise direction. The contacts 54 and 55 are included in the circuit 48, 49, and are normally closed. When it is desired to take a radiograph the lever 56 is moved upon the scale 57 to a desired setting, which has been 30 found by experiment to give a desired exposure for the subject to be radiographed. This movement of the lever 56 carries a zero stop 58 for the pin 53 toward or away from the movable contact 54 thereby varying the 35 distance thru which the pin is required to travel before opening the contacts 54, 55.

When the switch 50 is closed the X-ray tube begins to function, and as above described, the gear train is set into motion by 40 the action of the electromagnet 45. By the rotation of the motor element of the switch the pin 53 is carried forward to break the circuit, the rate of motion varying with the square of the voltage thereby varying the 45 exposure time inversely with the square of the voltage so that a substantially constant radiographic effect is produced. In other words, assuming a subject requiring an exposure of five seconds with a constant line 50 voltage at the transformer primary of 100 volts, the length of exposure will be automatically decreased to about 4.1 seconds should the line voltage rise to 110 volts. When the contacts have been opened, the 55 gear 44 strikes the blank space in the gear 51. When the magnet 45 is deenergized, the gears 44 and 51 are pulled out of mesh by the spring 59 and the pin 53 is returned to its initial position against the stop 58 by 60 the spring 60.

The automatic controller or variable time switch shown in Fig. 3 is the invention of Chester I. Hall, and is covered by a patent application, Serial No. 526,994, filed January 4, 1922, by Chester I. Hall. In a divisional application, Serial No. 634,864 I have made claims on the apparatus and method herein described whereby a constant radiographic effect is obtained by varying the current through the X-ray tube when the applied voltage varies.

70 What I claim as new and desire to secure by Letters Patent of the United States, is:

1. An X-ray apparatus adapted for operation from a source of electric energy of 80 variable potential which consists in an X-ray tube operating substantially independently of gaseous ionization, and means responsive to departures of operating voltage from a predetermined value for varying the 85 time-current factor of said discharge inversely in such measure as to secure a substantially constant radiographic effect.

2. An X-ray apparatus comprising an X-ray tube, a source of current subject to voltage variations connected to the electrodes of 90 said tube, means for producing at operating voltages a substantially constant current-carrying capacity in said tube and means 95 whereby the operation of said tube may be set for different time intervals, said means varying the time intervals inversely with the square of the operating voltage, in case said voltage varies, to secure a predetermined radiographic effect for any given 100 setting.

3. An X-ray apparatus adapted for operation with current of variable voltage which 105 consists of an X-ray tube, means for generating electrons at the cathode of said tube at a substantially constant rate, means for automatically regulating the length of time of operation of said tube as such inverse function of the supply voltage that the radiographic effect of X-rays generated by 110 said tube for a given setting is substantially constant.

4. An X-ray apparatus adapted for operation from a supply circuit of fluctuating voltage which consists of an X-ray tube having a cathode adapted to be heated, means for supplying said cathode with energy of 115 substantially constant voltage, and a motor-operated switch for timing intervals during which said X-ray tube is energized, connected in the supply circuit of said tube, said switch being provided with means for varying the time of operation of said X-ray tube for a given setting inversely with the 120 square of the supply voltage.

5. An X-ray apparatus comprising a main transformer, an X-ray tube having a cathode adapted to be heated, connections between the secondary winding of said 125 transformer and the main terminals of said 130

5 tube, a second transformer having a secondary winding connected to heat said cathode, a common supply circuit for the primary windings of said transformers, said second 50 transformer being constructed to deliver substantially constant heating current when supplied with current of variable voltage and switching means constructed to vary the length of operation of said tube to secure a substantially constant radiographic effect.

10 6. An X-ray apparatus comprising a transformer, an incandescent cathode type X-ray tube connected to the terminals of the 55 secondary winding of said transformer, means for heating the cathode of said tube to a substantially constant temperature, a switch in circuit with the primary of the transformer, means for setting said switch for different X-ray outputs, and means for varying inversely with the square of the supply voltage of the transformer the time of operation of said tube to secure a desired radiographic effect.

15 7. The combination of an X-ray tube, means for generating electrons at a substantially constant rate at the cathode of said tube, a supply circuit therefor, means for giving said tube a normal time setting, and 60 means responsive to variations of voltage in said circuit for varying the length of said setting inversely with said voltage variations to produce a predetermined radiographic effect.

20 8. An X-ray apparatus adapted for operation from a circuit of variable voltage, comprising an X-ray tube, circuits for operatively connecting said tube to said source, means for generating electrons at the 65 cathode of said tube at a substantially constant rate, means for setting the operation of said tube from said source for a predetermined output, and means for varying the length of time interval said tube is in operation in such measure as to secure for a given 70 setting a predetermined radiographic effect

regardless of voltage fluctuations of said source.

9. The method of operating an X-ray device by a current of fluctuating voltage 75 which consists in maintaining the current through said tube substantially constant while varying the time inversely in accordance with variations of the square of the applied voltage, thereby obtaining a substantially constant radiographic effect.

10. The method of operating an X-ray tube of the hot cathode type by an energy supply of fluctuating voltage which consists in heating the cathode of said tube with current of substantially constant potential and varying the time interval for a given time setting inversely in accordance with 80 variations of the square of the applied voltage.

11. In combination, an electric source subject to voltage variations, a translating device supplied thereby, means for connecting said device in circuit with said source, a time switch for automatically disconnecting said device after a time interval set at will, 85 said switch comprising means for varying the length of said interval inversely in accordance with the square of the voltage of the source in case the voltage varies.

12. In combination an electrical source subject to voltage variations, an incandescent cathode discharge device supplied thereby, means for heating said cathode to a substantially constant temperature, means for connecting said device in circuit with said source, and a time switch for automatically disconnecting said device after a set time interval, said switch comprising 90 means for varying said interval inversely in accordance with the square of the voltage of the source when said voltage departs from a predetermined value.

In witness whereof, I have hereunto set my hand this first day of July 1920.

WILLIAM D. COOLIDGE.
